METHOD OF AND APPARATUS FOR SOUND MODIFICATION

Richard M. White, East Cleveland, Ohio, assignor to Macoustic Engineering Company, Cleveland, Ohio, a corporation of Ohio

Application May 18, 1932, Serial No. 612,031
Renewed September 11, 1934

13 Claims. (Cl. 181—30)

The present invention, relating as indicated to a method of and apparatus for sound modification, is more particularly directed to a new, improved and simplified method and apparatus for modifying sounds of various frequencies, in which the method employed involves the splitting of the sound waves into various components and the recombining of these components in a different phase relationship as distinguished from sound absorption as now generally practiced by absorbing the energy of a sound wave or dissipating the energy of a wave by friction against a surface or within recesses or cavities in a surface. To the accomplishment of the foregoing and related ends, said invention, then, consists of the means hereinafter fully described and particularly pointed out in the claims; the annexed drawings and the following description setting forth in detail certain means and one mode of carrying out the invention, such disclosed means and mode illustrating, however, but one of various ways in which the principle of the invention may be used.

In said annexed drawings:—

Fig. 1 is a diagrammatic view illustrating a view of a simple system of two sound waves; Fig. 2 is another view of a simple system of two sound waves of opposite phase combined to show a zero resultant; Figs. 3 and 4 are diagrammatic views illustrating in its simplest form my improved and novel method of sound modification; Fig. 5 is a similar view showing a modified and more complete form of apparatus embodying my method of sound modification; and Figs. 6, 7, 8, 9, 10, 11 and 12 are other diagrammatic views illustrating various other modified forms of apparatus embodying my method.

Up to the present time, sound absorption has been universally carried out by allowing a sound wave possessing sound energy to strike a surface composed of material possessing numerous pores, openings or channels in which the sound waves enter, and in which the sound energy is converted into heat by repeated reflection against the walls of the pores, openings or recesses in the material. In this method and with such apparatus sound energy is actually absorbed by the conversion into heat through surface friction in the pores or recesses of the absorbing material.

This method of sound absorption, while effective, does not lend itself to convenient use, and in its use materials are ordinarily employed which gradually fill up with dirt by reason of their necessarily porous nature, with the result that the absorptive value of the material is not constant

and the material itself is not sanitary. In addition to these objections to the ordinary materials, it is difficult with most of such materials to introduce decorative effects or to place the surface of the material in condition for cleaning or painting, as any surface coating applied thereto naturally tends to close the pores or recesses and thereby reduce the effectiveness of the material as a sound absorbing medium. I am aware of the use of material of the type which I have referred to as a backing in a panel, in which the surface of the panel has an apertured hard plate provided with numerous minute openings through which the sound waves pass into the sound absorbing material behind the plate, and while this type of material presents an improvement for many purposes over the materials theretofore used, it still has the objections of relatively high cost, and a tendency to have its sound absorbing value reduced in use through the infiltration of dirt and foreign material. In addition to these objections, this type of sound absorbing material operates upon the same principle of conversion of sound energy into heat as the other materials referred to above, and by these materials I include fabrics of all sorts, compressed fibrous material, porous plasters and similar materials which have been employed for this general purpose.

My improved invention embodies a new and totally different method of sound absorption or modification, consisting essentially in the neutralization of the intensity of sound reflected from a structure by providing that structure with means to reflect varying fractions of the incident sound wave, while causing the reflected portions to differ in phase relationships with the first or surface reflected wave. By thus treating the sound waves as a combination of two or more waves of the same frequency traveling in the same direction but having varying amplitudes I can produce a resultant sound wave of the same frequency, the amplitude of which will depend upon the phase relationships of the two or more original waves. I have found it possible to provide apparatus which will combine the reflected portions of a sound wave in such a manner that the phase relationships will cause a maximum of interference so that the resultant reflected wave will be much lower in intensity than the original. A classical example of the effect which I have found it possible to secure in the modification of sound is found in the case of a tuning fork where there are zones of varying loudness as the listening mechanism is moved around the

fork in a complete circle, due to the interference between the waves of each branch of the fork caused by combinations of two waves of equal amplitude, but opposite phase.

To illustrate the operation of this principle in my method of sound modification, there is shown in Fig. 1 a simple system of two sound waves A and B traveling in the direction indicated and of the same frequency and amplitude. If the two sound waves A and B, traveling in the same direction and having the same frequency and amplitude, have the same phase the resultant sound wave A' is of a magnitude indicated in Fig. 1. If the second series of sound waves B is superimposed upon the first wave A so that the phase difference is exactly 180° the resultant sum of the two waves will be zero, as indicated by the line B', Fig. 2. If the two waves are combined in phase with each other, then the sum will be four times as great in intensity and twice as great in amplitude as either of the individual sound waves. The resultant is indicated as a straight line B' for the case where the two waves are 180° out of phase, in which condition the sound impulses have canceled or neutralized each other and no sensation of sound is perceptible to the human ear, as the ear is sensitive to vibratory motions only and transmits as sound only the result of motion imparted to it by the vibration of the ear.

With this known principle as a basis, I have developed a method of at least partial neutralization or cancellation of sound waves to produce a reduction in the intensity of sound striking 35 against a structure which I have developed to effect this modification or cancellation of sound waves. Referring now to Fig. 3, I have shown two surfaces D and E, spaced from each other, in which the surface D is a hard reflective surface provided with a series of openings therein. A sound wave X striking against the reflective surface of the outer perforated plate D is partially reflected therefrom, the reflected portion being indicated by the line x, and is partially transmitted therethrough, the transmitted portion being indicated by the line x'. The transmitted portion x' is reflected from the inner imperforate surface E, the reflected wave being indicated again by the line x'. This portion of the wave x' which is reflected from the surface E is partially transmitted through the plate D and is partially reflected therefrom. The transmitted portion is indicated by the line x'' and the portion reflected back from the plate D by the line Y.

This reflected wave Y strikes the rear plate E and is again reflected, a portion of it being transmitted through the plate D and is indicated by the line y and the reflected portion is indicated by the line Z. The reflected portion Z is again reflected from the plate E as the line Z, and of this wave a part again is transmitted through the plate D and indicated by the line z, and another portion is reflected back from the plate D and indicated by the line z'. This in turn is reflected from the rear plate E and again this reflected wave is partially transmitted and partially again reflected from the plate D.

I have found that it is desirable to so construct the surface or plate D that not over approximately 20% and not less than 2% of the total surface area is formed by the openings and approximately 80% to 98% of the total surface area is imperforate. A ratio of perforate to imperforate area determines the percentage of sound passed by the plate D at any one frequency. When

this ratio of perforated to closed area is some determinable value, say less than 6%, then for a frequency of 512 cycles per second the outer plate D (Fig. 3) will transmit 62% of the incident sound and will reflect 38%. Assuming in the example illustrated in Fig. 3 that the plate D has the property of passing 62% of the incident sound energy as above described and reflecting 38%, then the 62% of the initial sound energy may be represented by the line x' and this same amount of energy is of course reflected from the plate E back toward the plate D. Of this amount 62% is transmitted through the plate D and is represented by the line x''. 62% of 62%, or 38 1/2%, is again reflected and again indicated by the line Y. If the phase relationship between the surface wave X, which is reflected initially as the wave x, and the double reflected wave x'' is exactly 180° , the sum of the two waves will have an amplitude of only one-half of 1% of the original unreflected wave.

It is then necessary only to account for the portion of the double reflected wave that was returned from the inner side of the surface D to the surface E. If I let y represent the portion of the sound energy passed out of the system in the manner indicated, it will have a value of 14.6% of the original wave since it is the product of $62\% \times 38\% \times 62\%$. This wave, however, is in phase with the first reflected wave and tends to 30 augment the intensity thereof. The resultant of the first reflected wave with the second double reflected wave and the third wave (x+x''+y) is then $38\% + 14.6\% - 38\frac{1}{2}\%$, or 14.1%. By applying similar successive reflections to the system 35 it can be shown that the resultant intensity from an infinite number of reflections closely approximates the value of 9.9%. In other words, the system returns only 9.9% of the sound incident upon it, although there is no dissipation of sound through friction, and all of the dissipation or modification exerted on the sound wave is due entirely to the change in phase relationships. The phase relationships of the various components is dependent upon the frequency of the 45 original sound, the distance between the surfaces D and E and the angle of reflection.

In Fig. 4, I have shown diagrammatically a sound-absorbing panel consisting of an imperforate plate E, spaced perforate plate D, as in 50 the form of Fig. 3, and an additional spaced perforate plate F. The action of this construction will be similar to that diagrammatically illustrated in Fig. 2 and previously described, except that the sound returned will be still further modified by the splitting of the sound waves incident upon the surface D, a fraction of the sound wave being reflected and another fraction being transmitted through the openings in the plate D. The portion transmitted will be reflected from the 60 plate E and will be returned in a different phase relationship and therefore in such a way as to modify the reflected sound issuing from the structure as a whole.

In Fig. 5, I have shown a similar structure consisting of reflected plate E and perforated plates D, F and G arranged in spaced relationship. This structure will of course have an effect similar to that of Figs. 2 and 3, but will still more greatly modify the reflected waves. Similarly the structure of Fig. 6, consisting of reflecting plate E and spaced perforated plates D, F, G and H, will have a still greater modifying effect.

While I have explained that my system of sound modification differs from those previously em- 75

ployed, in that the energy of the sound is not absorbed, but is permitted to continue on and to be reflected in substantially its full intensity to neutralize or cancel the greater portion of the entire reflected sound, it is still possible to add to the sound modifying or absorbing effect of my system by combining with it certain features of previous systems. Thus in Fig. 7, for example, I have shown a structure composed of a reflecting plate L and spaced perforate plate K, which will have the sound-modifying effect of the structure illustrated in Fig. 2. This effect can, however, be increased by coating the adjacent surfaces of the plates L and K with sound-absorbing mate-

rial M. Either of the two adjacent surfaces of the plates L and K may be coated or both may be coated, and the amount of sound absorbed thereby will of course be deducted from the amount reflected, and by that amount the total sound reflected from the system will be reduced.

In Figs. 8, 9 and 10, I have shown perforated plates N, O and P, respectively, provided with variously shaped or sized openings R, S and T, respectively, and it will be evident that numerous arrangements of openings and forms of openings may be employed. I have found that the size and shape of opening can advantageously be varied, depending upon the frequency of sound vibration which is to be modified. Similarly, in a composite system or panel consisting of more than merely a single reflecting plate and a single perforated plate it is possible, by properly combining two or more plates provided with perforations, to greater advantage with plates having different sized and shaped openings and in this way to provide a composite unit which will have substantially any range of sound modification that is desired.

In Fig. 11, I have shown an apparatus for carrying out my improved system of modifying sound consisting of a substantially flat rear plate U and spaced perforated corrugated plates V and W. In this system it will be understood that the plates V and W are substantially parallel with each other and with the reflecting plate U as in the constructions previously described, but it is not necessary that all of the plates be level or smooth and slight corrugations such as are indicated in the structure of Fig. 11 have no detrimental effect upon the sound modifying action of the system.

In Fig. 12, I have shown a structure very similar to that of Fig. 11 and consisting of rear reflecting plate U' and perforated plates V' and W'. The plates V' and W' in this structure, however, each consists of a multiplicity of angularly related surfaces v' and w', which are so related with respect to each other and of such area that they jointly form partially closed chambers H. Such a system has a greater phase distortion than a system of the structure shown in Fig. 4, consisting of flat, smooth plates and may therefore for certain purposes be advantageously used in preference to a structure employing flat plates only.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:—

1. In a method of modifying sound, the steps which consist in interposing in the path of a

sound wave means capable of partially reflecting and partially transmitting therethrough portions of said wave, and then reflecting the transmitted portions of such wave in a phase relationship different to that of the portion initially reflected. 5

2. Sound modifying apparatus consisting of two spaced plates, one of said plates being capable of partially transmitting and partially reflecting sound waves incident thereupon, and the other of said plates being capable of reflecting the transmitted portions of sound waves passing through said first-named plate in a phase relationship different from that of the wave portion reflected from the first-named plate. 10 15

3. Sound modifying apparatus consisting of a series of spaced perforated plates, each of said plates being capable of transmitting a portion of the sound wave incident thereupon and of reflecting the remainder of such sound wave. 20

4. Sound modifying apparatus consisting of an imperforate plate, a plurality of perforate plates disposed approximately parallel to said imperforate plate and in spaced relationship therewith and with each other, said perforated plates being each capable of transmitting a portion of a sound wave incidentally and of reflecting in a different phase relationship the remainder of said sound wave. 25 30

5. Sound modifying apparatus consisting of an imperforate sound reflecting plate and a second perforated plate disposed approximately parallel to said imperforate plate, one of said plates being provided with sound absorbing means on the surface adjacent to said other plate. 35

6. Sound modifying apparatus consisting of an imperforate plate and a plurality of perforated plates arranged in spaced parallel relationship with said imperforate plate, said perforated plates having openings therein of different size and form and being capable of producing splitting of the sound wave incident thereupon and of producing interference with the reflected portions of sound waves of different frequencies. 40 45

7. Sound modifying apparatus consisting of an imperforate sound reflecting plate, and a second perforated plate disposed approximately parallel to said imperforate plate, each of said plates being provided with sound-absorbing means on the surface adjacent to said other plate. 50

8. Sound modifying apparatus consisting of an imperforate sound reflecting plate, and a second perforated plate disposed approximately parallel to said imperforate plate, each of said plates being provided with sound-absorbing means on the surface adjacent to said other plate. 55

9. A sound modifying apparatus consisting of an imperforate sound reflecting plate, and a second perforated plate disposed approximately parallel to said imperforate plate, one of said plates being provided with corrugations. 60

10. Sound modifying apparatus consisting of an imperforate sound reflecting plate, and a plurality of perforated plates arranged in spaced parallel relationship with said imperforate plate, said last-named plates being provided with corrugations. 65

11. Sound modifying apparatus consisting of an imperforate sound reflecting plate, and a plurality of perforated plates arranged in spaced parallel relationship with said imperforate plate, said perforated plates having openings therein of different size and form and one thereof being provided with phase-distorting corrugations. 70 75

12. Sound modifying apparatus consisting of an imperforate sound reflecting plate, a plurality of perforated plates arranged in spaced parallel relationship with said imperforate plate, said last-named plates being provided with corrugations and the corrugations in adjacent plates being so arranged as to form partially closed sound-receiving chambers.

13. Sound modifying apparatus consisting of an imperforate plate provided with sound ab-

sorbing material on one surface thereof, and a plurality of perforated plates arranged in spaced parallel relationship with said imperforate plate, the surfaces of said last-named plates facing the coated surface of said imperforate plate being provided with sound-absorbing material, and said last-named plates being provided with corrugations arranged to form partially closed chambers between adjacent plates. 5

RICHARD M. WHITE. 10
